DESIGN FOR AN ILLUMINABLE VANITY CASE

Pearl V. Aber, Los Angeles, Calif.

Application April 14, 1941, Serial No. 100,376

Term of patent 7 years

To all whom it may concern:

Be it known that I, Pearl V. Aber, a citizen of the United States, residing at Los Angeles, in the county of Los Angeles and State of California, have invented a new, original, and ornamental Design for an Illuminable Vanity Case, of which the following is a specification, reference being had therein to the accompanying drawing, forming part thereof, in which—

Figure 1 is a perspective view of an illuminable vanity case shown in a closed position, and illustrating my new design.

I claim:

The ornamental design for an illuminable vanity case, as shown.

PEARL V. ABER.
